UNITED STATES PATENT OFFICE

ARTHUR E. HOHMEISTER, OF CINCINNATI, OHIO, ASSIGNOR TO THE JOHN DOUGLAS COMPANY, OF CINCINNATI, OHIO, A CORPORATION OF OHIO

ELBOW HOUSING AND THE LIKE

Application filed September 20, 1929. Serial No. 394,019.

This invention relates to a cover housing for use with plumbing fixtures and the like and has for an object the provision of a simple and inexpensive construction which is easy to mount on and remove from a fixture.

Another object is to provide a readily attachable and detachable cover for elbow connections which is free from direct connection with the elbow or pipe concealed by it.

Another object is to provide a simple mounting means which is especially adapted for the mounting of porcelain vitreous housings.

These and other objects are attained by the means described herein and disclosed in the accompanying drawings, in which:

Fig. 1 is a fragmental perspective view of a tank and bowl with a housing of the invention covering the flush elbow connection.

Fig. 2 is a perspective view of the mounting means with the elbow in place and the cover removed therefrom.

Fig. 3 is a perspective view showing the parts in operative position about an elbow apart from the fixture.

Fig. 4 is a view partly in cross section showing the device in an operative position on a fixture.

Fig. 5 is an elevational view showing the manner of inserting the cover housing in a fixture assembly.

A flush tank such as 7 and a bowl 8 have a space between them across which extends a flush pipe 9, usually in the form of an elbow. In both the new and existing installations this flush pipe is visible and it becomes corroded and collects dirt, and is practically the only connection which presents difficulty of housing to shield it from the accumulation of dirt and to conceal it from view.

In the present invention a housing of any suitable shape is provided with a rear and bottom opening so that it may be seated about a flush pipe to cover the top and sides of such pipe or elbow 9 without contacting it and without any direct connection to the pipe. This is highly desirable because it avoids the difficulties and disadvantages which attend an attempt to fasten a housing upon a pipe or elbow which is covered by it. The flush pipe

is usually made of brass tubing and is likely to be crushed or dented if a careless workman tightens a clamp too tightly upon it.

In the present invention the housing is provided with side walls or aprons 10 and a front 11 connecting them. The opposite ends 12 and 13 of the housing are arranged to conform to and to abut the bottom of the tank 7 and the face of the bowl 8 in which a spud 14 receives the flush pipe. Integral lugs 15 on the aprons 10 have bottom faces 16 disposed at the rear thereof. It is to be noted that no manner of direct connection is necessary between the housing and the mounting means.

The lock nut 17 which fastens the valve in the bottom of the tank 7 is provided with outwardly extending lugs 18 with threaded bores 19 therein. A simple threaded stud 20 is adapted to be screwed into anyone of the threaded bores 19 which, in tightening the lock nut can be disposed closest the rear center line of the elbow 9. A curved yoke 21 has a perforation therein through which the stud 20 may pass and a wing nut 22 serves to support this yoke on the stud at any desired elevation.

From the foregoing it will be apparent that when the stud is introduced into one of the perforations 18 and the yoke and wing nut 22 are positioned loosely thereon, the housing may be readily positioned, as indicated in Fig. 5 so that the bottom faces 16 of the apron portion of the housing are above the yoke, whereupon the yoke may be turned transversely to a position in which both of the lugs 15 are supported by it. It will be noted that the width of the housing and the space between it and the elbow 9 will permit of this positioning and adjustment without any difficulty whatsoever. Thereupon by tightening up on the wing nut, the yoke will raise the outer ends of the apron until the entire top edge 12 of the housing is in abutment with the bottom of the tank 7. The movement to this position causes the opposite end of the housing to move into substantial abutment with the bowl 8 and the spud 14 thereon may support the inner face of the housing.

As indicated in Fig. 1 the housing may be made in such form as to harmonize with the style of the fixture to which it is applied. The arrangement however is such that any of the decorative forms or shapes are readily adapted to the invention and they provide ample open space at the rear to permit of facile attachment and detachment.

What is claimed is:

1. In a device of the class described the combination of a plumbing fixture having a lock nut, a lug on said nut, a threaded stud in the lug, a cover housing having a pair of lugs disposed on opposite sides of the stud and an adjustable yoke on the stud abutting the lugs for holding the cover housing in position on the fixture for concealing a flush pipe or the like attached to said fixture. 10
2. An elbow housing and mounting means comprising a housing having a pair of notched aprons and means comprising a lock nut having a stud, and an adjustable yoke on said stud for mounting the housing on a fixture carrying the lock nut and concealing a pipe projecting from the fixture. 15
3. In combination with a tank and bowl, of a lock nut on the tank, a flush pipe connecting the tank and bowl, a cover for the pipe and having lugs thereon, and an adjustable yoke for engaging the lugs on the cover for mounting the cover in position between the tank and bowl and removably securing the cover to the tank. 20
4. In combination a tank having a pipe securing nut, a bowl having a spud, a pipe extending from the said nut to the spud, a cover for the pipe, and means carried by the pipe securing nut and independent of the pipe for holding the cover to the tank and concealing the pipe. 25
5. A mounting means for a ceramic elbow housing and the like comprising a stud adapted for mounting adjacent a pipe, a perforate yoke slidable on the stud and means for holding the yoke in adjusted position upon the stud to clamp the housing upon a surface to cover the pipe. 30
6. In combination a tank, a bowl, a pipe connecting the tank and bowl and a detachable one-piece cover rigidly mounted between the tank and bowl for covering the pipe, said cover being independent of connection with the pipe. 35
7. In a device of the class described the combination of a valve lock nut for connection to a tank and a pipe, a threaded depending stud on said nut, a yoke slidable on the stud, a nut for the stud and a removable housing having lugs for engagement by the yoke and adapted to be secured to the tank and to cover the pipe. 40
8. In combination a lock nut having peripheral lugs with transversely extending threaded bores, a threaded stud for mounting in a bore in one of the lugs, a yoke having a bore for receiving the stud and a nut for adjusting the yoke on the stud. 45
9. In combination with a tank having a flush pipe elbow extending therefrom, of a threaded stud depending from the tank, a cover for the elbow having one end abutting the tank and means on the stud and engaging the housing for retaining the housing in position to cover said elbow. 50
10. In combination a tank, a bowl, a flush pipe elbow connecting the tank and bowl and a one-piece ceramic elbow-shaped cover extending from the tank to the bowl and fixed relative thereto independently of the pipe. 55
11. In combination a tank, a bowl, a flush pipe elbow connecting the tank and bowl and a one-piece channel-shaped ceramic elbow cover for the pipe and extending from the tank to the bowl, said cover being fixed relative to and independently of the pipe. 60
- In testimony whereof, I have hereunto subscribed my name this 17 day of September, 1929. 65
